H. J. HERRING.

ABUTMENT FOR WASHING MACHINES.

APPLICATION FILED JULY 7, 1915.

1,201,729.

Patented Oct. 17, 1916.

UNITED STATES PATENT OFFICE.

HARRY J. HERRING, OF LONG BEACH, CALIFORNIA, ASSIGNOR OF ONE-HALF TO CLYDE A. PAYNE, OF LONG BEACH, CALIFORNIA.

ABUTMENT FOR WASHING-MACHINES.

1,201,729.

Specification of Letters Patent. Patented Oct. 17, 1916.

Application filed July 7, 1915. Serial No. 38,539.

To all whom it may concern:

Be it known that I, HARRY J. HERRING, a citizen of the United States, residing at Long Beach, in the county of Los Angeles 5 and State of California, have invented a new and useful Abutment for Washing-Machines, of which the following is a specification.

My object is to make an abutment for a 10 washing machine having an oscillating beater working between and against foraminous abutments, and my invention consists of the novel features herein shown, described and claimed.

15 Figure 1 is a side elevation of a washing machine having an abutment embodying the principles of my invention, parts being broken away to show the details of construction. Fig. 2 is a top plan view as indicated 20 by the arrow 2 in Fig. 1. Fig. 3 is an enlarged fragmentary vertical sectional detail on the lines 3—3 of Fig. 2. Fig. 4 is a fragmentary vertical sectional detail on the lines 4—4 of Fig. 3. Fig. 5 is a horizontal section 25 on the lines 5—5 of Figs. 3, 4 and 6. Fig. 6 is an enlarged fragmentary sectional detail on a line parallel with Fig. 4.

The supporting frame 1 is simply a stand 30 having a top 2 upon which the tub 3 is removably mounted. The stand 1 as shown is in the form of a saw-buck, but the construction of the stand is not material, it may be a box or table, or the like.

The tub 3 is preferably constructed of galvanized iron and is square or rectangular in plan and has a sheet metal bottom 4 resting on the table top 2, and flaring sheet metal sides 5, 6, 7 and 8 extending upwardly from the bottom.

40 The cover frame consists of boards 9, 10 and 11 inserted horizontally just below the upper edge of the side pieces 5, 6 and 8 and secured by nails 12 driven through the metal into the edges of the boards, and a molding 45 13 placed in position to cover the upper edges of the metal.

The drain board 14 is inserted between the ends of the boards 9 and 11 opposite the board 10 and against the lower face of said 50 boards 9 and 11.

The cover 15 fits between the boards 9 and 11 and is connected with the board 10 by the hinges 16 and when in its closed position rests on the edge of the drain board 14.

55 The wringer support 17 extends upwardly

from the outer edge of the drain board 14 and splash boards 18 and 19 are inserted against the edge of the wringer board 17 and above the ends of the drain board 14 so as to let the drainage from the wringer back 60 into the tub.

Thin wooden strips are inserted upwardly against the inner edges of the boards 9, 10 and 11 and project inwardly to form the flange 20, covering the crack around the three 65 sides of the cover 15, so as to prevent the suds from slopping up around the edges of the cover.

The operating shaft 21 is mounted vertically through the center of the cover 15, there 70 being a bearing block 22 secured on top of the cover by bolts 23 and a flange 24 secured to the upper end of the shaft 21 and resting on the bearing block 22, said bearing block 22 serving to stiffen the cover and to provide 75 a good bearing for the shaft 21.

The operating crank 25 extends upwardly and outwardly from the upper end of the shaft 21 and has a handle 26 upon its upper, outer end.

80 The beater 27 is fixed upon the lower end of the shaft 21 and the foraminous abutments 28 and 29 are mounted directly opposite each other in a substantially straight line with the shaft 21, the beater 27 extending across this line so that by operating the handle 26 the beater may be oscillated. The ends of the beater 27 extend beyond the inner edge of the foraminous abutments 28 and 29 so as to strike the abutments as the 85 beater is oscillated.

85 The details of the beater 27 are as follows: The central portion or head 30 is rectangular in side-elevation and the fingers 31 extend from one end of the head, and the fingers 32 extend from the other end of the head. There are preferably three fingers 31 and three fingers 32, the spaces between the fingers being substantially equal to the width of the fingers. A wire or small rod 33 is bent 90 to form the portion 34 extending upwardly through the bases of the finger 31, the portion 35 extending parallel with the lower finger 31 from the lower end of the portion 34, the portion 36 extending upwardly from the 95 outer end of the portion 35 through the tips of the fingers 31 and the portion 37 extending inwardly from the upper end of portion 36, so as to make cross-bars for the fingers 100 and increase the effectiveness of the fingers. 110

A similar wire or rod is bent to form the portion 38 extending upwardly through the bases of the fingers 32, the portion 39 extending outwardly from the lower end of the portion 38, the portion 40 extending upwardly from the outer end of the portion 39 through the tops of the fingers 32, and the portion 41 extending inwardly from the upper end of the portion 40. The beater 27 is mounted upon the shaft 21 by extending the shaft 21 downwardly through the center of the head 30, there being a recess 42 extending from the lower face of the head and an arm 43 extending from the lower end of the shaft 21 and fitting into the recess 42, and a lug 44 extending upwardly from the arm 43 into the body of the head.

The plate 45 is secured against the side of the head 30 and has a flange 46 extending under the arm 43 to hold the beater head 30 from moving upwardly on the shaft 21.

The foraminous abutments 28 and 29 are substantially alike except that the abutment 28 is slightly shorter than the abutment 29, said abutment 28 extending upwardly from the bottom 4 along the side piece 7 to the lower face of the drain board 14 and the abutment 29 extending upwardly from the bottom 4, along the side piece 8 to the lower face of the board 10.

In Figs. 3, 4, 5 and 6 I have shown the details of the foraminous abutment 28 which are as follows: The foraminous body 47 is a section of coarse galvanized wire screen. The outer edge of the screen is covered by a binding 48 consisting of a strip of galvanized sheet iron cut to the desired width and having its edges folded upon itself and then the strip folded at the center upon the edge of the screen, as shown in detail in Fig. 5. Said strip consists of the edge portions 49 and 50 folded upon the intermediate portions 51 and 52, said intermediate portions being folded against opposite sides of the edge of the screen 47 and pressed tightly together, then solder 53 is applied to the bent edges 54 and 55, the object being to hold the edges of the screen firmly. In a similar manner a binding 56 is applied to the inner edge of the screen 47, the said binding 56 comprising the edge portions 57 and 58 folded inwardly upon the intermediate portions 59 and 60 and said intermediate portions 59 and 60 being folded upon opposite sides of the edge of the screen and pressed firmly together and held by solder 61 applied along the bent edges 62 and 63.

In assembling the screen 47 and bindings 48 and 56 the screen is made slightly bias so as to match the inclination of the side wall 7. A lower binding 64 is applied to the lower edge of the screen 47, said lower binding comprising a strip of galvanized sheet iron bent to form the attaching flange

65, fitting against the bottom 4 and secured by the line of solder 66, the portion 67 extending upwardly from the flange 65, the portion 68 folded against the portion 67 and extending downwardly from its upper edge, and the portion 69 extending upwardly from the lower edge of the portion 68, the lower ends of the bindings 48 and 56 and the lower edge of the screen 47 being inserted between the portions 68 and 69 and said portions being pressed tightly against the screen and bindings and secured by the lines of solder 70 and 71. The upper binding 72 is formed of a strip of galvanized sheet iron bent at its center upon itself and then the double thickness bent to form an angle-bar, said binding comprising the intermediate portions 73 and 74 bent upon themselves and the side portions 75 and 76 bent at right angles to the portions 73 and 74, the upper ends of the bindings 48 and 56 and the upper edge of the screen 47 being inserted between the portions 75 and 76 and said portions being pressed tightly together and secured by the lines of solder 77 and 78. In assembling the parts the foraminous abutment is sufficiently bias so that the flange 65 fits the bottom 4 and the flange formed by the portions 73 and 74 fits the lower face of the drain board 14 and the bolts 79 are inserted through the flange and through the drain board 14 to hold the abutment rigidly in place.

The details of the foraminous abutment 29 are identical with the details of the foraminous abutment 28 just described, and these details need not be repeated.

The beater 27 is considerably longer than the distance between the inner edges of the foraminous abutments 28 and 29 so that the beater overlaps the abutments and the beater is mounted crosswise of the line of the abutments, so that as the beater is oscillated the fingers on the ends of the beater will strike flatwise against the sides of the abutments simultaneously and will strike first one side and then the other.

The articles to be washed are placed in the tub with a sufficient amount of water, then the handle is operated to oscillate the beater and as the ends of the beater slam the clothing against the sides of the foraminous abutments, the water will pass freely through the abutments and through the fingers of the beater.

I am aware that washing machines have been made having oscillating beaters working between abutments and I do not claim such construction broadly.

I claim:

An abutment for a washing machine comprising a body of galvanized wire screen, a binding for the outer edge of the wire screen consisting of a sheet of galvanized iron having its edges folded upon itself and

then folded in the center against the sides of the wire screen, and securely soldered, a binding for the inner edge of the screen comprising a strip of galvanized iron having its edges folded upon itself and then folded in the center upon the edge of the screen and held in place by solder, a lower binding comprising a strip of galvanized sheet iron bent to form a flange adapted to be soldered to the bottom of the tub and a second portion extending upwardly from the flange, a third portion extending downwardly from the upper edge of the second portion and folded against the second portion, a fourth portion extending upwardly from the lower edge of the third portion,

the lower ends of the side bindings and the lower edge of the screen being mounted between the third and fourth portions and secured by solder, and an upper binding 20 consisting of a strip of galvanized iron folded upon itself and then the double thickness bent to a right angle, the upper ends of the side bindings and the upper edge of the screen being inserted between 25 the two vertical portions of the upper binding and secured by solder.

HARRY J. HERRING.
